4. A wagon having a body with a horizontal bottom of sheet metal, a bracket formed from sheet metal at a middle portion thereof into a substantially cylindrical form and with wings diverging rearwardly and outwardly and with a vertical gap at the rear of said cylinder between the wings, means for permanently securing said wings to the under side of the body, a sheet metal member secured to said wings closing said gap, said sheet metal member at its upper end terminating a distance below the bottom of the body, a bolster located transversely of the body underneath the lower end of the cylindrical portion of the bracket, a kingpin connected to said bolster and extending upwardly through the cylindrical portion of the bracket, a bearing for the upper end of the kingpin within said cylindrical portion of the bracket and below the bottom of the body, a pin releasably passing through said kingpin at its upper end above said bearing, said pin being accessible from the rear of said cylindrical portion of the bracket immediately below the bottom of the body, a bearing between the upper side of said bolster and the lower side of said bracket located around the kingpin, a tongue structure connected to the bolster and extending forwardly therefrom, and an axle having wheels one at each end located longitudinally of and at the lower portion of the bolster and connected therewith.

5. A construction as defined in claim 4, said bolster comprising a length of sheet metal of inverted generally channel form having spaced front and rear sides and an upper web through which said kingpin passes, said axle lying between said front and rear sides of the bolster near their lower edges said upper side of the bolster adjacent its middle portion inclining downwardly and outwardly away therefrom and securing clips around said bolster at the ends thereof clamping it to the axle.

6. In a wagon structure as described, a front axle unit comprising a horizontal axle, a wheel mounted at each end of the axle, a bolster of sheet metal of substantially channel form having an upper web and spaced depending sides located lengthwise of and over said axle, means connecting the bolster at its ends to the axle, a member located horizontally between the depending sides of said bolster adjacent the lower portions thereof and substantially midway between the ends of said bolster, a kingpin secured to said member extending in a substantially vertical direction therefrom through the upper side of said bolster, an upper tongue member of inverted channel form having a rear end portion passing over the upper side of the middle part of said bolster, said kingpin passing therethrough, a second tongue member of inverted channel form having its rear end located at the lower side of said bolster, means connecting said second tongue member with the bolster, said tongue members extending forwardly and converging toward each other, each adjacent its forward end having a portion of its upper web between its flanges removed and the flanges of one member passing within the flanges of the other at their forward meeting ends, a horizontal pivot pin passing through said forward meeting ends of the tongue members and a tongue through one end of which said pivot passes.

7. In a construction as described, a wagon body having a horizontal under side, a bracket secured to said under side having a front substantially vertical hollow portion extending downwardly near the front end of the body, spaced bearings one at the lower end of and one located thereabove, spaced from and within the hollow portion of the bracket, a kingpin passing through said bearings and extending below the bracket, releasable means securing the kingpin in place above the upper bearing, a transverse bolster in which the lower end portion of the kingpin is secured, supporting means on said bolster pivotally mounted to turn about a substantially horizontal axis substantially parallel to the length of the wagon body to which the king pin is secured at its lower end, said bolster where the kingpin passes upwardly therethrough being slotted to permit a relative turning of the bolster about said axis with respect to said kingpin, an axle parallel to and connected with the bolster, a wheel at each end of the axle and a tongue connected with the bolster extending forwardly therefrom.

8. A wagon having a body, a bracket extending downwardly from the forward end of the body, an axle having wheels at its ends, a bolster connected to said axle and extending upwardly therefrom, a king pin pivotally connected at its lower end to the lower part of said bolster and extending upwardly into said bracket, said bolster having an opening through which said king pin passes, said opening being elongated longitudinally of said axle, a bearing for the upper end of said king pin in said bracket and said bolster and surrounding said king pin.

9. The elements of claim 8 in which said bolster has a bearing supporting surface curved concentric with the pivotal connection of the lower end of the king pin.

10. A wagon having a body, a bracket extending downwardly from the forward part of the body, an axle having wheels at its ends, a bolster attached to said axle and extending upwardly therefrom, a king pin attached to said bolster and extending into said bracket, an embossment on the upper part of said bolster and surrounding said king pin, a tongue member shaped to receive said embossment and attached thereto, a bearing between said bracket and said bolster and a bearing in said bracket for the upper end of said king pin.

11. The elements of claim 10 combined with a second tongue member attached at one end to said first tongue member and attached at its other end to said axle.

FREQUENCY SELECTOR AND CALIBRATOR

Paul Stead Gay, Charlotte, Mich., assignor to
 Wilcox-Gay Corporation, Charlotte, Mich., a
 corporation of Michigan

Application March 19, 1943, Serial No. 479,724

11 Claims. (Cl. 74—10)

1

My invention relates to means for operating radio tuning devices and, more particularly, to a means for setting a radio transmitter or receiver tuning device in such a manner that it may immediately be tuned to a specific frequency, this specific frequency being variable at the will of the operator.

In the construction and operation of portable transmitting and receiving radio equipment, especially that type of portable equipment which is intended to be carried entirely by a single individual, and which has now come to be generally known as the "walkie-talkie," it is essential that as many operations as possible be simplified or, in fact, dispensed with.

Thus, when an operator in the field desires to adjust his instrument to receive the signals from a specific transmitter, it is desirable that he be enabled to make this adjustment in the simplest possible manner.

The field operator may, for instance, be required to transmit or receive on a particular tuned frequency, while on occasion it may be necessary for him to transmit or receive on other frequencies. After tuning his instrument to such other frequencies, it then is necessary for him, when he desires to transmit or receive on the particular assigned frequency, to carefully adjust his instrument to that frequency. Then once again when he tunes for another frequency and must return once more to the original particular frequency, the same kind of adjustment must be made.

Such adjustments obviously require visual and aural attention, as well as a manual operation, and thus impede or at least interfere, to some extent, with the field operator's primary function which usually is to observe and report or receive reports and transmit them.

A primary object of my invention is the provision of means in connection with portable radio devices of the type above set forth whereby the operator may, when he desires to return to the particular or most frequently used frequency, do so by a momentary manual operation without the necessity for any visual or aural attention.

The essence of my invention includes the arrangement of a stop or retaining member in such a manner that it may be connected to or disconnected from the tuning device. When connected to the tuning device it may be connected thereto at any angular position desired and then integrated therewith so that the tuning device or tuning dial may automatically be returned to this predetermined angular position.

2

A corollary object of my invention, therefore, is the provision of an engaging or stop member in connection with a rotatable tuning member, the same being connectable thereto or disconnectable therefrom; and when connected thereto the same may be arranged in any predetermined angular position with respect to the rotatable tuning member to permit the automatic setting of said rotatable tuning member at the desired angular position.

Thus an object of my invention is to provide a means of first tuning the receiving or transmitting set to a given frequency in connection with additional means to return to that particular frequency at any desired time.

A further object of my invention is the provision of means facilitating the calibration of a tuning device, the said means being so arranged that the adjustment thereof will not interfere with the tuning of the device.

Heretofore in such calibrating devices, the operations necessary to calibrate the various members tended to shift the members out of their exact desired setting.

An object of the invention is to provide a securing means for the calibrating members, the operation of which is in a plane normal to that of the ordinary movement of the tuning members so that this operation will not tend to disturb the tuning members.

Another object of my invention is the use in connection with the tuning and calibrating device above set forth of means operable by the snap action of a convex member to lock the various locking or calibrating members in place.

These and many other objects will in part be apparent and, where not apparent, pointed out in the following description and drawings, in which:

40 Figure 1 is a front view of my novel tuning means.

Figure 2 is a rear view of the locking device taken on line 2—2 of Figure 3 and looking in the direction of the arrows.

45 Figure 3 is a cross-sectional view taken on line 3—3 of Figure 1, looking in the direction of the arrows.

Figure 4 is a view of a portion of the tuning device of Figure 1 showing the calibrating means and taken on line 4—4 of Figure 3, looking in the direction of the arrows.

Figure 5 is a cross-sectional view of the locking elements taken on line 5—5 of Figure 1, looking in the direction of the arrows.

50 Figure 6 is a view in perspective broken away

showing the complete tuning device of Figure 1 with the calibrating device thereof disconnected and the calibrating means tightened.

Figure 7 is a view corresponding to that of Figure 6 showing, however, the locking device in locking position and the calibrating device in loosened position.

Figure 8 is a view showing the locking knob and bolt of the locking device of Figure 5.

Figure 9 is a side view of the clamping member 10 of Figure 5.

Figure 9a is a view of a blank from which the member of Figure 9 is formed.

Referring now to Figures 1 and 3, I have here shown my tuning device which consists of a shaft 10 which in turn is an integral extension of the shaft 11 on which variable or rotatable elements of the condenser unit 12 are mounted.

An operating knob 14 is secured in any suitable manner as, for instance, by the set screw 15 on the end of the shaft 10 in order to facilitate the rotation thereof.

As is seen in Figure 5, a bushing 17 is mounted over the shaft 10 and 11 and secured thereto in any suitable manner, as for instance by the set screw 18, in such a manner that it rotates therewith. The bushing 17 passes through the opening 20 in the front panel 21 of the housing of the device. A clamping plate 22 is rigidly secured at the outer end of the bushing 17 in such manner that it rotates therewith. This clamping plate 22 cooperates with the locking device in the manner hereinafter described.

A tuning pointer consisting of a flat member 24 is loosely mounted on the bushing 17 immediately upon the clamping plate 22. As is seen in Figures 3, 6 and 7, the entire tuning pointer consists of the loosely mounted plate 24 and an indicating member 25 which is secured to the plate 24 in any suitable manner as, for instance, by the screws 27, and which projects substantially beyond the periphery of the clamping plate 22 and over the calibrated dial 30.

The indicating member 25 may be formed from any suitable transparent material having a line marking 31 thereon or attached therein for indicating the particular portion of the calibrating dial over which the pointer travels.

Obviously, my invention need not be limited to this particular form of the pointer but any suitable pointer may be used for this purpose provided that its construction include the loose mounting thereof on the periphery immediately behind the clamping plate 22.

The plate 24, which forms the base of the pointer, is slotted at 32 to receive the rivet 33. The rivet 33, as may be seen particularly in Figure 6, is a stepped rivet, the head 35 of which is rigidly attached to the clamping disk 22. The body of the rivet 33, as has been pointed out, passes through the slot 32 in the pointer and the base 36 of the rivet is sufficiently wide to prevent dis-assembly of the pointer and the rivet slot 32 in the member 24. This permits the pointer to be rotated with respect to the clamping disk 22 through a restricted arc.

The locking member 38 has an opening 39 therein through which it may be mounted on the rivet. This opening 39 is substantially equal in diameter to the diameter of the main body of the rivet 33 so that the locking member 38 has substantially no movement with respect thereto. The locking member 38 comprises, as shown in Figure 6, a convex dish-shaped area 40. In addition, it comprises an integral extension 41 which

facilitates the operation thereof. This extension will hereafter be referred to as tab 41.

When the member 38 and its convex area 40 is in the position shown in Figure 6, the pointer 24-25 is locked relative to the clamping disk 22 and has no movement with respect thereto. This is so because the apex of the convex area 40 bears against the inside of the clamping disk 22 while the edge 42 of the convex area 40 bears against the plate 24. Consequently, the pointer has no movement with respect to the clamping disk 22 and any rotation of the knob 14, which thus causes rotation of the shaft 10-11 and of the clamping disk 22, will result in exactly similar rotation of the pointer 24-25.

If, however, the operator finds that when he is tuned to a station of a particular frequency while the indication given by the pointer is of a frequency slightly above or slightly below the frequency to which he is in tune, he may quickly adjust his pointer so that it will indicate the exact frequency to which his set is tuned and so that all other frequencies will thus be indicated exactly.

For this purpose he then unlocks the pointer and moves it slightly to the correct frequency and locks it once more. This unlocking action is shown in Figure 7. By pulling the tab 41 of the locking plate 38 toward the tuning knob 14, the convex area 40 is by a snap action forced into a convex shape on the opposite side. This type of snap action is well known and needs no further explanation. It occurs wherever a spherical depression is made in a piece of spring metal and thereafter the ends of the metal are bent toward the convex side. When a sufficient bend has occurred, the convex area will be snapped to the other side. Similarly, on a reverse bend, the convex area will snap over once more.

Here, as shown in Figure 7, depression of the extension 41 has caused the convex area to snap to the other side; while the apex of the convex area is now, in Figure 7, pressed against the plate 24 of the pointer 24-25, the edge 42 is no longer pressed against either the clamping plate 22 or the plate 24. The plate 24 now may move freely within the restricted arc permitted by the slot 32 therein. The pointer 24-25 is now moved so that the marking 31 thereon coincides exactly with the correct frequency on the dial 30 and when this has been done, the tab 41 is now pushed toward the pointer 25, thus forcing the convex area 40 of the locking plate 38 through center once more to the opposite side to the position shown in Figure 6 where it locks the pointer once more and re-integrates it as a single unit with the shaft 10-11, the knob 14 and the locking disc 22.

By this simple means the tuning device may be recalibrated as often as may be necessary so that an exact indication may be given. The length of the slot 32 in the pointer 24-25 may be as long as is necessary for any anticipated deviation or error. In ordinary cases, such deviation or error from the showing of the exact frequency may be no more than 1 or 2 markings on the dial 30, so that the slot 32 need be only of sufficient length to permit compensation for this error.

Heretofore, in the use and arrangement of such calibrating devices, the locking means which locked the pointer in the reset position was of such a nature that movement thereof to locking position tended to cause a rotation or shifting of either the condenser shaft or of the pointer. For this reason the locking of the pointer after calibration had been made either required a great

deal of caution or it was virtually impossible to lock the same in correct position without some shift.

In my invention this locking is obtained by a movement in a plane which contains the axis of shaft 10, said plane being normal to the plane of the movement of the members which are to be locked. It can thus be seen that any force in the plane of the movement of the locking member can not cause rotation of the rotatable members.

Thus, when the operator desires to correct the calibration of his device, he pulls the tab 41 toward the knob 14 which moves the locking plate 38 axially. He then shifts the pointer 24—25 to the correct position and, after having made this shift, now pushes the tab 41 toward the pointer 25, thus moving the convex area 40 of the locking plate 38 axially once more into the tight frictional engagement of Figure 6. None of the locking movements thus have any tendency to disalign the now calibrated members.

The clamp disk 22, in addition to providing for the locking action of the pointer when it is desired to recalibrate the same, also provides for the much more important action of making it possible for the operator of the device to retune the same to a desired frequency by a simple manual operation without the necessity for visual or aural attention.

This action is also shown at the lower half of the broken perspective views of Figures 6 and 7 and is also set forth in connection with the other figures.

Referring for the moment to Figures 2, 3 and 5, it will here be seen that a notched disk 50 is securely mounted on a bushing 51 in such manner that it is virtually integrated therewith. The bushing 51 is rotatable about the bushing 17; and as may also readily be seen from Figure 5, the notched disk 50 is mounted behind the front plate 22 of the chassis.

The rotatable bushing 51 extends through opening 29 in the front plate 21 of the chassis and on the exterior thereof has secured thereto and integrated therewith the arm 52. Thus it may be seen that rotation of the arm 52 will result in rotation of the notched disk 50 and vice versa.

The outer end of the arm 52 carries the clamp member 53 which comprises a threaded bolt 54 having the knurled knob 55 on the outer end thereof and passing through the tapped perforation 56 in the end of the arm 52.

An additional clamping lock 58 is captured between the outer surface 60 of the end of the arm 52 and the inner surface of the knurled knob 55.

The shaft 10 passes through a slot 82 in the opposite end of the clamp member 58. The clamp member is therefore held by the knurled knob 55 at one end and the shaft 10 at the other end. Figures 8 and 9 show the construction of the bolt 54 and the clamp member 58. It will be seen that the end of the clamp through which passes the bolt 54 is folded back upon itself.

The hole 83 is positioned in such a way that two ears 84 are formed on the folded over portion of the clamp member 58. When the bolt 54 is passed through the hole 83, the groove 85 in the bolt 54, which is shown in Figure 8 comes within the plane of the ears 84. These ears are bent inward toward the center of the bolt so that they serve as retainers for the bolt 54. It can thus be seen that if the bolt 54 were to shake loose or become disengaged from the tapped perforation 56 in the end of the arm 52, it cannot become lost as it is retained by the clamp 58 which is in

turn captured by the shaft 10 between the knob 14 and the clamping disc 22. The width of the slot 82 in the end of the clamp member 58 and the diameter of hole 83 in the opposite end are of such dimensions that when the knurled knob 55 is tightened, rotating motion cannot be imparted to the clamping plate 22.

When the knob 55 is rotated so that the bolt 54 enters further into the tapped perforation 56 of the arm 52, the clamp member 58 is thus brought into tight engagement with the edge of the clamp plate 22. The area of the clamp member 58 in the vicinity of the knurled knob 55 bears tightly against the outer surface of the clamp plate 22 and pushes it tightly against the surface 60 of the end of the arm 52, thus locking the arm 52 to the particular desired portion of the edge of the plate 22. When this locking operation is completed, the notched disk 50 on the inside of the front plate of the chassis will now rotate in exactly the same way as all of the other rotatable members.

This rotation of the knob 14 will, through the shaft 10—11, cause the variable condenser rotatable elements to rotate. It will also effect rotation of the clamp plate 22. Clamp plate 22 will, in the manner previously described, also effect an exactly corresponding rotation of the pointer 24—25; and by reason of the locking action of the bolt 54, 55 and the clamp member 58 in connection with the arm 52, this rotation of the knob 14 and the plate 22 will also cause an exactly similar rotation of the arm 52 and of the bushing 51 and hence of the notched plate 50.

When the clamping action is removed by rotation of the head 55 of the bolt 54 to disengaging position, then rotation of the knob 14 and its associated members will not result in rotation of the notched plate 50, or, at least, any member which engages the notched plate 50 will not in such case impede the rotation of the condenser tuning device.

The notched plate 50, when it is, by means of the tightening of the head 55 of the bolt 54, engaged with the plate 22 for rotation upon operation of the knob 14, may be in turn engaged by the snap action locking member 70 (see Figures 2, 3, 6 and 7).

The action of the locking member 70 is more clearly seen in the broken perspective Figures 6 and 7. The locking member 70 is a snap action member consisting of a flat piece of spring metal having a convex area 71 formed therein. The base of the metal member 70 is secured in any suitable manner as, for instance, by the bolts 73 and nuts 74 to a lug 75 at the bottom of the front 21 of the cabinet.

The lug 75 serves as a spacer in order to position the plate 70 in appropriate relation to the notched disk 50. As may readily be seen in Figures 2, 6 and 7, the notched disk 50 is provided with the notch 76.

The locking member 70 has at its upper end opposite to the pointing attachment a round lug 78 secured thereto in any suitable manner as, for instance, by a rivet; the said lug having a diameter substantially equal to the width of the slot 76. Preferably, the diameter of the button or lug 78 should be such as to permit it readily to enter into the slot 76 but so that it will nevertheless completely fill this slot when it has entered the same to prevent movement of the notched plate 50. A tab 80 is secured in any suitable manner as, for instance, by the rivets 81 to the locking plate 70. The locking plate 70 is so arranged

that when the tab 80 is depressed from the position shown in Figure 6 to the position shown in Figure 7, the convex area 71 will be forced through center to the opposite side and the spring metal locking member 70 will be snapped to a position where the locking lug or button 78 will be urged into engagement with the surface of the notched disk 50.

When disengagement is desired, the lifting of the lever or tab 80 from the position shown in Figure 7 to the position shown in Figure 6 will again cause the convex area to be forced through center so that the locking button or lug 78 is now urged away from the notched plate 50 in the manner shown in Figure 6.

When the locking member is pushed by the tab 80 into the position shown in Figure 7, then as has above been pointed out, the button or lug 78 engages against the surface of the notched plate 50. Now when the notched plate 50 is rotated to a position where the notch 76 thereof moves opposite the button 78, the button 78 will snap into the notch and this inter-engagement will prevent further rotation of the notched plate 50.

In use, the operator may adjust the equipment to a particular frequency so that when it is desired to return to this frequency he may do so without the necessity for further visual or aural attention.

After having calibrated the pointer 24—25 so that it accurately indicates the correct frequencies on the dial 30, he moves the tab 80 in a downward direction as shown in Figure 7. The knurled knob 55 is then loosened and the arm 52 is moved to a position immediately below the knob 14 at which point the locking button 78 is engaged with the notch 76. He then tunes the instrument by rotation of the knob 14 until the desired frequency has been obtained, whereupon he tightens the knurled knob 55. This procedure results in locking the tuning mechanism at the frequency selected. Raising the tab 80 disengages the locking button 78 from the notch 76 and permits normal operation of the tuning control. Whenever it is desired to return to the preselected frequency the operator merely moves the tab 80 into its downward position, places his finger beside the knurled knob 55 and pushes it down to the position where the tuning mechanism locks by virtue of the engagement of the locking button 78 with the notch 76.

In actual operation, of course, the operator need not and does not concern himself with the various types of engagement or inter-engagement of elements within the chassis.

The operation of the device as far as the operator is concerned falls into the following four elements:

- (a) Calibration of the dial.
- (b) Setting of the control unit so that it may be returned to a desired frequency.
- (c) Tuning to other frequencies.
- (d) Returning to a preselected frequency.

A. In calibrating, the operator performs the following steps:

- 1. He rotates the knob to select a definite frequency.
- 2. He pulls the tab 41 toward the tuning knob 14.
- 3. He sets the pointer to indicate the selected frequency.
- 4. He pushes the tab 41 toward the pointer 25.

The tuning system is then properly calibrated.

B. To set the control unit so that it may im-

mediately be retuned to a desired frequency, the operator may proceed along the following steps:

1. He moves the tab 80 to its downward position.

2. He loosens the knurled knob 55.

3. He moves the arm 52 to the position where the locking mechanism engages.

4. He tunes the instrument to the desired frequency.

5. He tightens the knurled knob 55.

The set is now adjusted so that it may immediately be retuned to the selected frequency.

C. To tune to another frequency the operator proceeds as follows:

1. He moves the tab 80 to its upper position.

2. He tunes the instrument.

D. To retune to the pre-selected frequency the operator performs the following steps:

1. He depresses the tab 80.

2. He places a finger beside the knurled knob 55 and pushes it down to the position where the tuning mechanism locks.

Thus, without any visual or aural attention, he is enabled immediately to return to the pre-selected frequency.

It will thus be seen that the above operations may be performed in a minimum of time as a direct result of the design features disclosed.

In the utilization of so-called "walkie-talkie" devices in the field, it is clear that emergencies may arise which will not permit the operator to divert his attention to the tuning of this set to the particular or pre-selected frequency. In the utilization of the device of my present invention, the operator, having made the necessary preliminary preparations long before the emergency could have arisen, is at the time of the emergency able by two simple manual operations which require neither visual nor aural attention to tune to the necessary frequency. He is thus enabled to effect this tuning operation while maintaining the necessary observation which his duties or position may call for and the visual and aural alertness necessary for his own protection.

In the foregoing I have set forth my invention by describing one specific embodiment thereof. While I have shown this embodiment only in connection with tuning devices for radio transmitters and receivers, it is clear that my invention may have many and varied uses wherever it may be necessary or desirable quickly to rotate a member to a pre-selected position while at the same time making said member freely rotatable until it is necessary to rotate the same to that selected position.

Many variations in the specific embodiment above set forth and in the various applications of my invention should now be obvious to those skilled in the art. Accordingly, I prefer not to be bound by the specific disclosures herein but only by the appended claims.

I claim:

1. A tuning device for radio apparatus comprising a rotatable shaft, a member rotatably journaled on said shaft, lock engaging means carried by said rotatable member, and means for selectively connecting said rotatable member to said shaft for rotation therewith, and a locking member selectively engageable with said journaled member and disengageable therefrom, said journaled member comprising a disk, said lock engaging means comprising an opening in said disk and said locking member comprising a stud movable into engagement with the surface of said disk 75 at a radial distance from the center thereof equal
